UNITED STATES PATENT OFFICE.

WILLIAM H. SCHIRMER, OF CLEVELAND, OHIO, ASSIGNOR TO THE W. B. McALLISTER COMPANY, OF CLEVELAND, OHIO, A CORPORATION OF OHIO.

WHEEL AND METHOD OF MAKING SAME.

Application filed June 5, 1920. Serial No. 386,845.

To all whom it may concern:

Be it known that I, WILLIAM H. SCHIRMER, a citizen of the United States, and a resident of Cleveland, county of Cuyahoga, and State of Ohio, have invented a new and useful Improvement in Wheels and Methods of Making Same, of which the following is a specification, the principle of the invention being herein explained and the best mode in which 10 I have contemplated applying that principle, so as to distinguish it from other inventions.

The present invention, relating, as indicated, to wheels and method of making same, is directed to an improvement on the invention described and claimed in the co-pending application of William B. McAllister, entitled "Steering wheel and method of making same," filed February 11, 1920, Serial No. 357,936. In that application there 20 is described a wheel or other curved article made by winding upon itself a thin strip of flexible material, such as veneer, and cementing or gluing the contacting surfaces of such strip, and allowing them to set in 25 that condition.

The present invention involves also a wheel built up of a strip of thin material, such as veneer, in which the contacting surfaces of the material are cemented or glued together 30 and allowed to set in that condition. I have found, however, that substantially the same strength can be secured in such a wheel, and the same economy of manufacture, by the use of a series of strips instead of one, this 35 series of strips being coiled in the same manner as the single strip. My improved wheel possesses one important advantage over that of the application referred to, in that several of the strips which are used may be of 40 very inferior material, so long as at least one solid strip is used. This advantage is secured because as the several strips are each supported or backed up by the others the chance of breakage when a strip is bent at a 45 weak spot or knot is practically eliminated. To the accomplishments of the foregoing and related ends, said invention, then consists of the means hereinafter fully described and particularly pointed out in the 50 claims.

The annexed drawing and the following description set forth in detail certain mechanism embodying the invention, such disclosed means constituting, however, but one

of various mechanical forms in which the 55 principle of the invention may be used.

In said annexed drawing:—

Fig. 1 is a plan view of a steering wheel constructed in accordance with my invention; Fig. 2 is a section on the line 2—2, Fig. 60 1; and Fig. 3 is a similar section of the same wall when turned down to the finished dimensions.

My improved wall is made by taking a series of strips of veneer 1, 2, 3, and 4, of 65 which, one strip, such, for example, as the strip 1, need be of good clear wood, while the other strips may be of an inferior grade of wood, or may even be broken or cracked, without detracting from the strength of the 70 finished ring. I start to coil the strip 1 in any suitable manner, and if convenient, usually about a suitable mandrel, and after coiling this strip for a quarter of a revolution I insert between the strip and the mandrel a second strip of wood 2. After coiling these two strips through another quarter of 75 a revolution I insert a third strip 3, and after finally coiling through three-fourths of a revolution, a fourth strip 4, after which 80 all of the strips are coiled together, the resistance of these strips to bending serving to maintain them in close contact and tending to prevent the unwinding of the strips so long as the free ends are held. As the 85 strips are coiled the contacting surfaces are given a coat of suitable cementing material, such as water-proof glue, and after the entire wheel has been coiled it is suitably clamped and allowed to set for a time sufficient to harden the glue, after which the 90 wheel may be turned down to any desired finished cross-section, which I have shown in Fig. 3.

The strips of veneer must be of a thickness 95 allowing them to be bent to the desired radius of curvature without special preparation, such as soaking steaming and the like. What this thickness may be will accordingly depend upon the curvature desired. 100 The approximate permissible ratio between the thickness of the strip and the radius of curvature should be not less than one to forty. In vehicle wheels, steering wheels and articles of similar size the strips may 105 vary from one eighth of an inch downward. If the wheel is designed to constitute the rim of a steering wheel, as shown in Fig. 1, the

various strips 1, 2, 3 and 4 are provided with suitably arranged openings or notches, adapting them to fit over the beveled ends 5 of the arm 6 of the spider 7 of the steering 5 wheel, so that as the wheel is coiled it is formed about the spider and is thus permanently engaged therewith, and cannot be removed except by breakage of the entire rim.

10 It is desirable that the several strips used should start at 90 degree intervals around the wheel, and should terminate after making two or two and half turns around the wheel. Each of the strips 1, 2, 3 and 4 are 15 beveled off, as shown at 8 for instance on the strip 1, to a feather edge, and if the wheel is made in this manner the outer and inner walls of the wheel will be found to be practically concentric, and should require little, 20 if any, turning down, except of course for the purpose of giving the wheel the desired cross-sectional form.

Other forms may be employed embodying the features of my invention instead of 25 the one here explained, change being made in the form or construction, provided the elements stated by any of the following claims or the equivalent of such stated elements be employed, whether produced by 30 my preferred method or by others embodying steps equivalent to those stated in the following claims.

I therefore particularly point out and distinctly claim as my invention:—

35 1. In a method of making annular arti-

cles, the steps which consist in coiling a thin strip of veneer upon itself, and coiling a second strip with the first named while starting such second strip after the first.

2. In a method of making annular articles, 40 the steps which consist in coiling a plurality of thin strips of veneer together into an annulus while starting such strips at intervals.

3. In a method of making annular articles, 45 the steps which consist in coiling a plurality of thin strips of veneer together into an annulus, and starting such strips 90° after each other in such coiling.

4. In a method of making annular articles, 50 the steps which consist in coiling a plurality of thin strips of veneer having bevelled ends together into an annulus, and starting such strips 90° apart.

5. An annulus comprising a series of 55 strips of thin veneer cemented together, such strips starting at equidistant intervals around the periphery of said annulus and each strip having overlapping contact with the adjacent strips and having bevelled ends. 60

6. An annulus comprising a series of strips of thin veneer coiled about each other and cemented together, such strips having bevelled ends and each strip having overlapping contact with the adjacent strips and 65 terminating at equidistant intervals about such annulus.

Signed by me, this 2nd day of June, 1920.

WILLIAM H. SCHIRMER.
